CLAIM

The ornamental design for a multifunction control and display panel for a measuring instrument, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of the multifunction control and display panel for a measuring instrument according to the present invention.

The multifunction control and display panel is flat and therefore the sides and rear of the drawings are not ornamented and omitted.
